UNITED STATES PATENT OFFICE.

JOSEPH C. LOHEC, OF SAN ANTONIO, TEXAS.

VALVE-GRINDING DEVICE.

1,293,133.

Specification of Letters Patent. Patented Feb. 4, 1919.

Application filed August 29, 1918. Serial No. 251,948.

To all whom it may concern:

Be it known that I, JOSEPH C. LOHEC, a citizen of the United States, and a resident of San Antonio, in the county of Bexar and State of Texas, have made certain new and useful Improvements in Valve-Grinding Devices, of which the following is a specification.

My present invention relates generally to valve grinding devices, and more particularly to an arrangement whereby the several valves of a multi-cylinder engine or motor may be simultaneously ground, my object being the provision of a simple, inexpensive apparatus, the structure of which provides for ready interchangeability, repair and adjustment of the working parts, as well as ready attachment of the device in operative position, and its removal therefrom.

In the accompanying drawing which illustrates my present invention:—

Figure 1 is a side view partly in section illustrating the practical application of my invention, and,

Fig. 2 is a plan view thereof.

Referring now to these figures, my invention contemplates the provision of a valve grinding apparatus which includes a support in the form of a U-shaped bracket 10, having upper and lower horizontal extensions 11 and 12, respectively, the latter of which is provided with openings for the reception of bolts 13 and the like, by means of which it may be rigidly secured upon an engine or motor, a portion of which is seen at 14 in Fig. 1, adjacent to the line of valves 15.

The upper extension 11 carries a rigid cross arm 16 adjacent its free end, and is also provided with an upright stud 17, to which is pivoted one end of an operating lever 18, having an intermediate longitudinal slot 19, for a purpose which will be presently described.

The cross arm 16 has a plurality of bearing openings communicating with slots 20, for the reception of the upper portions of valve grinding rods 21, each being removable through the respective slot for repair or substitution of parts, and having an upper crank portion 22 above the cross arm. The crank portions 22 of the series of valve grinding rods are loosely connected by connecting arms 23, and the upper crank portion 24 of a vertical shaft 25 also engages these connecting arms 23, and is in turn ex-

tended through the slotted opening 19 of the operating lever 18. This shaft 25 is extended vertically through openings in the upper and lower extensions 11 and 12 of the bracket 10, and oscillation thereof by movements of the operating lever 18 in opposite directions are transmitted through the connecting arms 23 and the several crank portions 22 to the various valve grinding rods 21, whose lower ends have yokes and pins 65 or other devices at 26 for engaging the several valves 15.

The valve grinding rods are furthermore held downwardly against the rods 15 in use, and under uniform pressure by virtue of a spring 27 coiled around each of the rods and compressed to the desired tension between the rigid cross arm 16, and spring bearing plate 28, held by a cross pin 29 at a point intermediate the ends of the rod. 75

The several rods 21 may also be guided by a lower cross arm 30 if desired, through which the rods are extended, and in case this lower cross arm is utilized, it will be slotted in the same manner as previously described 80 in connection with the cross arm 16, so that the several valve grinding rods may be individually or independently removed for purposes of repair or substitution of parts.

It is obvious therefore, that my invention 85 provides for uniform engagement and pressure upon the various valves of a series thereof, as well as for simultaneous grinding movement, so that the process of regrinding the valves may be carried out in a comparatively short space of time, and with minimum work. 90

It is obvious, furthermore, that my invention provides an extremely simple, inexpensive apparatus for the above purpose, 95 which will be effective in use, and the moving parts of which may be readily detached for purposes of repair, adjustment and substitution.

I claim:—

1. The combination of a vertical series of valve grinding rods having valve engaging means at the lower ends thereof, and having upper crank portions, of a supporting bracket, a cross arm carried by said bracket and in which the several rods are journaled, a shaft journaled in the bracket and having an upper crank portion, connecting rods joining the crank portions of said shaft and said valve grinding rods, and an operating 110

lever pivoted on the bracket and engaging the crank portion of the said shaft for the purpose described.

2. A valve grinding apparatus comprising a support, a cross arm carried by the support, a plurality of valve grinding rods removably journaled in the said cross arm to oscillate therein, and having valve engaging means at one end, an operating lever pivoted on the support, means between the operating lever and the opposite ends of said valve grinding rods for simultaneously oscillating the latter, and a spring adjacent each of said valve grinding rods engaged between a portion of the same and the said cross arm, as described.

3. A valve grinding apparatus comprising a U-shaped supporting bracket having upper and lower extensions, a rigid cross arm carried by the upper extension of the bracket and having a plurality of openings, and slots communicating with said openings, a plurality of vertically disposed valve grinding rods journaled at their upper portions in the said openings and shiftable into and out of the same through said slots, said valve grinding rods having valve engaging means at their lower ends, and having upper crank portions, the latter located above the cross arm, springs carried by the several rods, and compressed between portions thereof and the said cross arm, and an operating lever pivoted on the support, means between the operating lever and the opposite ends of said valve grinding rods for simultaneously oscillating the latter, and a spring adjacent each of said valve grinding rods engaged between a portion of the same and the said cross arm, as described.

ver pivoted on the supporting bracket and having connection with the several crank portions of the said valve grinding rods to 35 simultaneously oscillate the latter.

4. A valve grinding apparatus comprising a U-shaped supporting bracket having upper and lower extensions, a rigid cross arm carried by the upper extension of the bracket 40 and having a plurality of openings, and slots communicating with said openings, a plurality of vertically disposed valve grinding rods journaled at their upper portions in the said openings and shiftable into 45 and out of the same through said slots, said valve grinding rods having valve engaging means at their lower ends, and having upper crank portions, the latter located above the cross arm, springs carried by the several 50 rods and compressed between portions thereof and the said cross arm, an operating lever pivoted upon the supporting bracket, a shaft journaled through the extensions of said supporting brackets and having upper crank 55 portions and engaged by the operating lever, and connecting rods connecting the said crank portions of the shaft with the crank portions of the said valve grinding rods, as described.

JOSEPH C. LOHEC.
